M. UHL

TOOL

Filed April 18, 1923

INVENTOR
Matthäus Uhl,
BY C. P. Goebel
ATTORNEY

UNITED STATES PATENT OFFICE.

MATTHÄUS UHL, OF DONAU, GERMANY.

TOOL.

Application filed April 18, 1923. Serial No. 632,831.

To all whom it may concern:

Be it known that I, MATTHÄUS UHL, a citizen of the Republic of Germany, and a resident of Ulm, a/d, Donau, Germany, 5 have invented certain new and useful Improvements in Tools, of which the following is a specification.

This invention relates to tools and more particularly to an improved pliers, the invention having for its primary object to provide a tool of this character with interchangeable jaws and means for easily and quickly connecting like or unlike jaws to the relatively movable handle members of 15 the pliers.

In one embodiment of the invention, I may provide the crossed pivotally connected handle members with slotted or bifurcated terminal arms, said arms being connected by 20 a fixed pin extending transversely across the slot. The interchangeable jaws are each provided with a tongue having a curved recess opening upon one of its side edges and undercut walls at the inner end of the 25 tongue. The end edges of the bifurcated arms of the plier members are obliquely inclined and beveled to coact with said undercut end walls of the jaw elements, when said tongues are moved into the slots in said 30 arms and the pins engaged in the recesses in the tongues. In this manner the jaw elements are held in detachably connected relation with the plier members projecting longitudinally from the bifurcated arms 35 thereof.

It is a further general object of the invention to provide a tool of the above character which is simple and practical in its construction and may be manufactured and 40 sold at comparatively small cost.

With the above and other objects in view, the invention consists in the improved pliers and in the form, construction and relative arrangement of the parts thereof as will be 45 hereinafter more fully described, illustrated in the accompanying drawing and subsequently incorporated in the subjoined claims.

In the drawing wherein I have illustrated several desirable embodiments of the inven-

tion and in which similar reference characters designate corresponding parts throughout the several views:

Figure 1, is a side elevation of a pliers illustrating one embodiment of the invention;

Figure 2 is a plan view thereof:

Figure 3 is a side elevation partly in section of the pliers with the jaws disconnected therefrom;

Figures 4 and 5 are detail views of the 60 complementary plier jaws;

Figure 6 is a fragmentary elevation partly in section, illustrating the manner of connecting the jaws to the plier members;

Figure 7 is a horizontal section taken on 65 the line 7—7 of Figure 6;

Figure 8 is a detail perspective view of 70 one of the interchangeable plier jaws; and

Figures 9 and 10 are side and plan views, 75 respectively illustrating the slightly modified form of the invention.

Referring in detail to the drawing and more particularly to Figures 1 to 8 thereof, 5 and 6 respectively designate the two plier members having the usual reversely 75 curved hand engaging portions. Adjacent one of their ends, these members are reduced in thickness and disposed in cross-intersecting relation, as clearly shown in Figure 6 of the drawing and connected by 80 the transverse pivot pin 7. The reduced pivot receiving portion of each plier member has an off-set longitudinally projecting arm 8 disposed out of longitudinal alignment with the handle portion of said member. This arm is forked or bifurcated to provide the slot 9 having its inner end wall obliquely inclined as at 10. The end edges of the spaced parts of the arm are likewise 85 obliquely inclined, as shown at 11, in an 90 opposite direction to the end wall 10, said end edges 11 being also transversely beveled for a purpose which will hereinafter appear.

Intermediate the ends of each of the bifurcated arms 8, a pin 12 is transversely disposed across the slot 9 and securely fixed in the spaced parts of said arm. These pins

provide means whereby variously shaped jaws may be interchangeably connected to or interlocked with the relatively moveable plier members. To this end, each jaw 13 is 5 provided upon one end with a longitudinally projecting tongue 14, beveled or undercut walls 15 being provided at the inner end of this tongue and obliquely inclined across the width of the jaw. A slot or recess 16, 10 preferably of arcuately curved form, is cut into the tongue 14 from the inner edge thereof, the entrance throat 17 to said slot being located adjacent to the undercut end walls 15 and said slot receding or curving 15 away from said end wall 18, to its inner closed end.

Upon reference now to Figure 6 of the drawings, it will be seen that in connecting the jaw element to each plier member, the 20 jaw is first positioned at an angle to the bifurcated arm 8 and the tongue 14 of the jaw is inserted into the slot 9 so as to position the transversely disposed pin 12 in the entrance throat 17 of the walls 18. The jaw 25 13 is then turned or moved outwardly to a position in alignment with the arm 18. The pin 12 is so located with respect to the end edges 11 of the arm that in this turning movement of the jaw said pin will exert a 30 camming action against the curved wall of the slot 16 and thereby cause the undercut obliquely inclined walls 15 of the pliers to closely contact with the beveled or inclined end jaw 11 of the arm 8. In this manner, the jaws are securely though detachably 35 connected to the plier members so that in the movement by manipulation of the plier members in the use of the tool, the jaws will remain in their longitudinally extending 40 positions with respect to the bifurcated arms 8.

In Figs. 9 and 10 of the drawings I have illustrated an alternative embodiment of the invention, wherein instead of providing the 45 bifurcated arms on the plier members, each jaw 13' has a bifurcated end portion 8' which provides a slot 9' to receive a tongue 14' projecting from the pivoted end of the plier member. In this case, the transverse pin 50 12' is carried by the jaw element and connects the spaced parts of the bifurcated end 8' thereof. The tongue 14' on the plier member is provided with a slot 16' which receives said tongue. It will thus be seen that this 55 construction involves a reversal of the arrangement of the co-operating parts above described. It will be understood that the form of the gripping portions of the jaws is immaterial and in addition to the form 60 of jaw shown in Figure 9, I may employ jaws of various other forms or shapes in connection with either of the described embodiments of the invention, a further example of such different jaw shapes being 65 illustrated in Figure 8 of the drawings.

From the foregoing description considered in connection with the accompanying drawing, the construction, manner of use and several advantages of the present invention will be readily understood. It will be apparent that I have succeeded in providing a tool which will be of great serviceability in practical use. As shown in Figure 9, the jaws connected to the plier members may be of different forms in accordance with the 75 particular purpose for which the tool is to be used. Since the forms and shapes of the jaws which might be provided, are quite numerous, I have not undertaken to illustrate and describe all of the different 80 constructions of jaws which might be provided for interchangeable connection with the pivotally connected members of the pliers, but have illustrated a few of the conventional forms of such jaws. It is also apparent that although I have herein referred to a certain specific construction of the plier members and the jaws, the details thereof may be varied to a certain extent without 85 effecting the efficiency of the device. Accordingly it is to be understood that I reserve the privilege of resorting to all such legitimate changes in the form, construction and arrangement of the several structural parts of the invention without departing 90 from the spirit and scope of the invention 95 as claimed.

I claim:

1. A pliers comprising pivotally connected members each terminating at one end in a longitudinally projecting bifurcated arm, a transversely positioned pin connecting the spaced parts of each arm, and interchangeable jaws each having a tongue at one end adapted for insertion into the slot of the 100 arm of one plier member, said tongue having an arcuately curved slot to receive said pin, the jaw adapted to be turned on said pin into longitudinal alignment with the 105 arm.

2. A pliers comprising pivotally connected members each terminating at one end in a longitudinally projecting bifurcated arm, a transversely positioned pin extending across the slot between the spaced parts 115 of the arm, and interchangeable jaw members adapted to be connected with said arms and each having a tongue at one end for insertion into the slot in the arm and said tongue having an arcuately curved slot opening upon one edge of the arm to receive said pin, said jaw having oppositely beveled walls at the inner end of the tongue and the spaced 120 parts of the arm having beveled end edges, said pin coacting with the curved walls of the slot in said tongue when the jaw is turned into alignment with said arm to cause said beveled faces on the tongue and arm to closely engage each other.

3. A pliers comprising pivotally connected 130

members, jaws adapted to be detachably connected to said members, one of the parts being provided with a tongue for insertion into a slot provided in the other part, said 5 latter part having a fixed pin extending transversely across the slot thereof and said tongue being provided with an arcuately curved slot to receive said pin, said pin coacting with the walls of the slot to retain

the jaw in operative relation to the plier member.

In testimony that I claim the foregoing as my invention, I have signed my name hereunder.

MATTHÄUS UHL.
